V. D'IORIO,
BARBER'S HAIR CLIPPER,
APPLICATION FILED FEB. 15, 1917.

1,233,202.

Patented July 10, 1917.

UNITED STATES PATENT OFFICE.

VINCENZO D'IORIO, OF NEW YORK, N. Y.

BARBER'S HAIR-CLIPPER.

1,233,202.

Specification of Letters Patent. Patented July 10, 1917.

Application filed February 15, 1917. Serial No. 148,710.

To all whom it may concern:

Be it known that I, VINCENZO D'IORIO, a subject of the King of Italy, and a resident of the borough of Bronx, county of Bronx, 5 city and State of New York, have invented certain new and useful Improvements in Barbers' Hair-Clippers, of which the following is a specification.

The main object of my invention is to automatically guide the clipping mechanism away from the surface being treated in such manner that a gradual and uniform increase of distance is attained, resulting in a prescribed curvature of trim as hereinafter set forth,—the invention consisting in the specific construction and arrangement of parts described and claimed, and the distinctive feature being the use of a contact roller, actuating gear, screw and spring mechanism 20 by which the bearing plate is forced apart from the shearing mechanism by the passage under pressure of the roller over the surface under treatment, and the automatic return to normal position assured as soon as the implement is removed from said surface, or the pressure relaxed.

In the accompanying drawings,

Figure 1, is a side elevation of my improved hair clipping device, my auxiliary surface bearing plate being shown as spaced apart from the clipping mechanism, as in use, $x-x'$, representing the surface traversed;

Fig. 2, is a side elevation of the clipper head with the auxiliary bearing plate closed, as when not in use;

Fig. 3, is a top view of the clipper head;

Fig. 4, a view of the under side thereof;

Fig. 5, is a section taken upon planes of 40 line 5—5, Fig. 3;

Fig. 6, is a diagram illustrating the function of my improved hair clipping device.

The hair clipping mechanism is essentially the same as that heretofore used, consisting of the base plate B, secured rigidly to the spring socket b, which is formed integral with the fixed handle b'; the clipping blade c, reciprocated by the hand lever c'; and the cap plate a, secured to the fulcrum stud b^a, 45 by the thumb nut b^a—the hand lever c', being actuated against the resistance of a spring in the socket b, in the usual manner.

The new parts are the auxiliary bearing plate p, the contactual roller r, (see particularly Figs. 4, and 5) mounted on the under side thereof, the screw shafts s, s, torsion

springs t, t, and adjuncts. Thus the auxiliary bearing plate p, is formed with two perpendicular posts p', p', slidably mounted in recesses formed for them in the base plate B, 60 cutter blade c, and cap plate a, and it is also preferably formed with a series of parallel slots p^x, (Fig. 4) through which hair clippings may escape from between the base plate B, and said auxiliary bearing plate p. 65

The lower ends of the screw shafts s, s, are mounted in the rear portion of the auxiliary bearing plate p, and carry bevel gears s', s', which mesh with corresponding bevel gears r', r', secured to the journals of the contactual roller r, which latter is mounted in bearings p², p², on the under side of the auxiliary bearing plate p. The screw shafts s, s, pass through openings formed for them in the base plate B, and their screw-threaded upper 75 ends s², s², engage with stationary nut arms a', a', integral with the cap plate a.

Encircling each screw shaft s, between the base plate B, and the stationary nut arms a', a', is a coiled torsional spring t, secured at 80 its lower end to the base plate B, and at its upper extremity to said screw shaft s. The tendency of these springs is constantly to turn and hold said screw shafts s, in normal position, as in Fig. 2, with the auxiliary plate 85 p, closed against the base plate B. When the roller r, is pressed against a resistant surface, as say, x, x', Figs. 1, and 6, and made to traverse the same, its bevel gears r', r', cause the shaft gears s', s', to rotate the screw 90 shafts s, s, against the resistance of the coiled torsional springs t, t, thereby causing the stationary nuts a', a', to force the screw shafts s, s, downward, so as to separate the auxiliary bearing plate p, from the base plate B, 95 the guide posts p', p', admitting of this movement and insuring the proper alinement of parts. As a result the distance between the auxiliary bearing plate p, and the cutting blade c, will be gradually increased as the 100 roller r, advances over the resistant surface, causing the clipping to be done in a curve, and clipping the hair in gradually and uniformly increased lengths as indicated diagrammatically in Fig. 6, in which x, represents the starting point and x', the finish.

When the roller r, is relieved from pressure and removed from the resistant surface x, x', the springs t, t, immediately rotate the screw shafts s, s, in the opposite direction, causing the stationary nuts a', a', to retract the said screw shafts s, s, until the 110

auxiliary plate *p*, again rests against the base plate *B*, and the parts are restored to normal condition and relationship, ready for the next clipping operation, when the same 5 action will be repeated if the roller *r*, is forcibly made to traverse a resistant surface. Thus, supposing the curves *x*, *x'*, in Fig. 6, to represent the contour of the back of the neck and lower rear portion of the head of a 10 person having a hair trim, it is obvious that the graduation of clip from practically nothing at *x*, to a maximum of length at *x'*, may be readily effected with as much ease as an ordinary close "crop" would be made 15 by the usual barbers' "clippers" as heretofore known and used.

This implement is designed for use exclusively for the purpose designated; *i. e.*, that of trimming the hair at the back of the head 20 and neck, or for effecting a graduated "short cut" for the whole head if desired, starting from close to the skin at the lower rear and sides of the head and gradually extending to a maximum of length of hair 25 above or at top; and all this may be expeditiously accomplished without special skill on the part of the operator because my graduating apparatus is automatic in action and requires no more time nor care than that involved 30 in an ordinary hair "crop" close to the skin as made by barbers' "clippers" now in use, the scope of which is limited, as before intimated to the function of cutting off the hair near its roots.

35 What I claim as my invention and desire to secure by Letters Patent is,

1. In a hair trimming device of the character designated, in combination, hair clipping mechanism, a contactual roller, a gear 40 mounted thereon, a screw shaft on which is mounted a gear meshing with that mounted on said roller, a fixed nut engaging said screw shaft, and a coiled torsional spring attached at one extremity to said screw 45 shaft and at the other extremity to a fixed part, for the purpose described.

2. In a hair trimming device of the character designated, in combination, hair clipping mechanism, a bearing plate, a contactual roller mounted thereon, a screw shaft on 50 which is mounted a gear meshing with that mounted on said roller, a fixed nut engaging said screw shaft, and a coiled torsional spring attached at one extremity to said screw shaft and at the other extremity to a 55 fixed part, for the purpose described.

3. In a hair trimming device of the character designated in combination, hair clipping mechanism, a bearing plate mounted thereon, and formed with a guide post positioned in recesses formed for it in the structure of said hair clipping mechanism, a contactual roller mounted on said bearing plate, gears rigidly connected with said contactual roller at each end thereof, screw shafts 60 engaging with fixed nuts on the casing of the hair clipping mechanism, gears on the lower ends of said gear shafts meshing with the gears on the ends of the contactual roller, and torsional springs coiled around said 65 screw shafts and attached thereto and to fixed parts, for the purpose described.

4. In a hair trimming device of the character designated, in combination, hair clipping mechanism, a bearing plate mounted 75 thereon and formed with two guide posts positioned in recesses formed for them in the structure of said hair clipping mechanism, a contactual roller mounted on said bearing plate, gears rigidly connected with said contactual roller at each end thereof, screw shafts 80 engaging with fixed nuts on the casing of the hair clipping mechanism, gears on the lower ends of said gear shafts meshing with the gears on the ends of the contactual 85 roller, and torsional springs coiled around said screw shafts and attached thereto and to fixed parts, for the purpose described.

VINCENZO D'IORIO.
